UNITED STATES PATENT OFFICE.

HENRY HARRISON LAMB, OF FOUNTAIN CITY, TENNESSEE.

DISPENSING-MACHINE SUPPLY.

Application filed February 10, 1920. Serial No. 357,513.

To all whom it may concern:

Be it known that I, HENRY HARRISON LAMB, a citizen of the United States, residing at Fountain City, in the county of 5 Knox and State of Tennessee, have invented a new and useful Improvement in Dispensing-Machine Supplies, of which the following is a specification, reference being had to the accompanying drawing.

10 My improvement relates particularly to supplies for machines for dispensing matches, one-by-one, from the interior of the dispensing structure.

15 The object of the invention is to provide such supplies in compact and effective form for dispensing such articles gratuitously as a matter of convenience, or for a price. In the latter case coin-controlled mechanism should be associated with the dispensing 20 structure. It is also contemplated that advertising may be associated with the supplies. In the form shown in the drawings provision is made for advertising, and the coin controlled mechanism is omitted from 25 the dispensing structure, the delivering mechanism being actuated manually.

In the accompanying drawings,

Fig. 1 is a perspective view of an apparatus in which my improvement is to be 30 used;

Fig. 2 is an upright section on the line, 2—2, of Fig. 3;

Fig. 3 is a plan, the lid or top of the apparatus having been removed;

35 Fig. 4 is an upright section on the line, 4—4, of Fig. 2;

Fig. 5 is a horizontal section on the line, 5—5, of Fig. 2;

40 Fig. 6 is an upright section on the line, 6—6, of Fig. 3.

Referring to said drawings, A is the front wall of the body of the dispensing apparatus. B is the right hand side wall. C is the left hand side wall. D is the back wall 45 of the body of the machine. E is the base of the machine. Within the base is a floor, F. A lid, G, extends across the upper end of the machine and is joined to the rear part of the body by a hinge, G¹. On the 50 upper edge of the front wall, A, is an eye, G⁴, which extends through a slot, G², on the lower forward edge of the lid. A padlock may be placed on the eye, G⁴, to secure the lid. An upright partition, H, extends from 55 the side wall, B, to the side wall, C, and

upward from the floor, F, nearly to the lid, G.

Within the compartment formed by the walls, B, C and D, and the partition, H, is a removable magazine, I, in which is a 60 long ribbon, I¹, of paper or similar pliable material. Said ribbon is a little wider than the length of a match, and on one side of the ribbon are placed matches, I², the matches being arranged crosswise and 65 spaced from each other chosen distances and secured to the ribbon by means of a suitable adhesive or in any other desired manner which will permit the detaching of the matches from the ribbon by the means hereinafter described. The ribbon is folded 70 upon itself, the folds running horizontally and transversely to the height of the magazine. This results in bringing match-bearing faces against each other. To save space 75 within the magazine, the folds are so arranged as to allow the matches of a downward-directed face to extend into the spaces between the matches supported by the next lower upward-directed match-bearing face. 80 These magazines loaded with a ribbon bearing matches as described are to be manufactured in quantity and furnished to those who have these dispensing machines. For charging the machine, the lid, G, is to be 85 raised and the lower end of the magazine inserted in the magazine compartment and the magazine then moved downward to the limit.

A chute, J, is placed forward of the partition, H, and transversely to the side walls, B and C. The upper end of the chute terminates close to the upper edge of the partition, H. From there the chute extends downward and forward on a curved course 90 and opens through the port, J¹, in the lower part of the wall, A, and immediately behind the forward extension of the base, E. Immediately above and forward of the forward wall, J², of the chute is a guide roller, 95 K, which is horizontal and parallel to the upper edge of said wall and is supported by the inner side walls, B¹ and C¹. The space between said roller and said edge is only sufficient to allow the passing of the paper ribbon, I¹, after the matches, I², have been removed from the sheet. The ribbon is inserted between said sheet and said edge with the matches on the lower face of the sheet, so that the forward movement of the 105 110

ribbon will bring the matches successively against said edge. The ribbon can not pass without the removal of the matches from the ribbon. The ribbon is drawn forward, 5 by mechanism to be described, with sufficient force to cause the upper edge of said chute wall to force the match free from the ribbon.

On the front part of the lid, G, is a window, G³. Behind the window is a guide roller, K¹, and a feed roller, K², which are parallel to the roller K, and are supported by the inner side walls, B¹ and C¹. Immediately below the feed roller, K², is a second 15 feed roller, K³, which bears upward against the roller, K². The roller, K³, is also supported in the inner walls, B¹ and C¹, and has a shaft, K⁴, extending outward through the wall, B. Outside of said wall said shaft 20 supports a small hand wheel, K⁵, adapted to be engaged by the operator for turning the wheel and said shaft and the roller, K³. Between the walls, B and B¹, a ratchet wheel, K⁶, surrounds and is fixed to said shaft, and 25 a spring pawl, K⁷, is secured to the inner wall, B¹, in position to bear against the teeth of said ratchet wheel to prevent reverse turning of the roller, K³.

The ribbon is placed beneath the roller K, 30 and over the rollers K¹ and K², and between the rollers, K² and K³. The engagement of the ribbon between the last two rollers is such as to cause the forward movement of the ribbon when the roller, K³, is turned by 35 turning the hand wheel, K⁵, clockwise as viewed in Fig. 2.

The space between the front wall, A, and the chute, J, is a chamber into which the ribbon is deposited after it has passed the 40 rollers.

The ribbon passes behind the window, G³; and so closely to the latter as to clearly expose the upper face of the ribbon to view through the window. Advertising may be 45 placed upon the upper face of the ribbon, the face opposite the face to which the matches are attached. While the machine is at rest, the advertising which is opposite the window remains exposed to view, and 50 whenever the hand wheel is turned to draw the ribbon forward to release a match for discharge through the chute, other adver-

tising surface on the ribbon will be brought to view behind the window.

The matches or similar articles are preferably attached to the ribbon, I, by lines of adhesive, I³, extending lengthwise of the ribbon, so that the adhesive makes only a limited engagement with the matches. Two such engagements between the match and 60 the ribbon will ordinarily be sufficient. The material of the ribbon will have to be so strong and the adhesive will have to be so weak as to avoid tearing the ribbon during the detachment of the matches. 65

I claim as my invention,

1. An article of manufacture for use in a dispensing machine, said article comprising a flexible ribbon and matches arranged transversely to the ribbon and secured to 70 one face of the ribbon by adhesive holding the match by a force which is less than the force which would be required to tear the ribbon or to break the match, substantially as described. 75

2. An article of manufacture for use in a dispensing machine, said article comprising a flexible ribbon and matches arranged transversely to the ribbon and secured to one face of the ribbon by means holding the 80 match by a force which is less than the force which would be required to tear the ribbon or to break the match, substantially as described.

3. As an article of manufacture for use 85 in a dispensing machine, a magazine comprising a receptacle and a flexible ribbon and matches secured transversely to one face only of the ribbon by means permitting removal of the matches by a force which 90 is less than the force which would be required to tear the ribbon or to break the matches, the ribbon being in the receptacle and folded back and forth upon itself to bring parts of the match bearing face of the 95 ribbon toward each other and the matches on each such part extending into the spaces between the matches on the opposing such part, substantially as described.

In testimony whereof I have signed my 100 name, this 30th day of January, in the year one thousand nine hundred and twenty.

HENRY HARRISON LAMB.
